Primary Examiner — T Chase Nelson

Assistant Examiner — Rachel Wolfe

(57) **CLAIM**

The ornamental design for a light assembly as shown and described.

DESCRIPTION

1. Light assembly
- 1.1: Perspective
- 1.2: Perspective
- 1.3: Front
- 1.4: Back
- 1.5: Left
- 1.6: Right
- 1.7: Top
- 1.8: Bottom
- 1.9: Enlarged
- 1.10: Enlarged

The broken lines depict portions of the Light assembly that form no part of the claimed design; reproductions 1.9 and 1.10 are enlarged views of portions labeled “1.9” and “1.10” in reproduction 1.1 respectively; the dash-dot-dash lines and the labels in the reproductions are for the purpose of depicting the boundaries of the enlargements that form no part of the claimed design.

1 Claim, 10 Drawing Sheets
